(57) **CLAIM**

The ornamental designs for an exercise bike, as shown and described herein.

DESCRIPTION

FIG. 1 is a perspective view of an exercise bike configured in accordance with a preferred embodiment of the present invention;

FIG. 2 is a right side elevational view thereof;

FIG. 3 is a left side elevational view thereof;

FIG. 4 is a front elevational view thereof;

FIG. 5 is a rear view thereof;

FIG. 6 is a top elevational view thereof; and,

FIG. 7 is a bottom elevational view thereof.

Broken lines, where utilized, are for illustrative purposes only and are not intended to limit the claimed design to the features shown in broken lines.
